UNITED STATES PATENT OFFICE.

JOHN P. BEATTY, OF CHARLOTTE, NORTH CAROLINA, ASSIGNOR OF ONE-THIRD TO JOE W. ARMSTRONG AND ONE-THIRD TO TURNER R. ARMSTRONG, BOTH OF CHARLOTTE, NORTH CAROLINA.

DUMP-BODY FOR AUTOTRUCKS.

1,319,986.

Specification of Letters Patent. Patented Oct. 28, 1919.

Application filed May 13, 1918. Serial No. 234,227.

To all whom it may concern:

Be it known that I, JOHN P. BEATTY, a citizen of the United States, residing at Charlotte, in the county of Mecklenburg 5 and State of North Carolina, have invented a new and useful Dump-Body for Autotrucks, of which the following is a specification.

The device forming the subject matter 10 of this application is a dumping body adapted to be assembled with an automobile frame, and one object of the invention is to provide means whereby the body may be rotated horizontally and be tilted vertically, 15 with respect to the frame.

Another object of the invention is to provide novel means for holding the body in adjusted position, against rotation in a horizontal plane with respect to the frame. 20

Another object of the invention is to provide novel means for tilting the body vertically. 25

A further object of the invention is to provide novel means for opening and closing the end gate of the body. 30

A further object of the invention is to provide novel means for holding the body releasably against tilting movement in a vertical plane. 35

It is within the province of the disclosure to improve generally and to enhance the utility of devices of that type to which the present invention appertains. 40

With the above and other objects in view, 35 which will appear as the description proceeds, the invention resides in the combination and arrangement of parts and in the details of construction hereinafter described and claimed, it being understood that, 40 within the scope of what is claimed, changes in the precise embodiment of the invention shown can be made without departing from the spirit of the invention.

In the accompanying drawings:— 45 Figure 1 shows in side elevation, a device constructed in accordance with the present invention, Fig. 2 is a top plan of the structure shown in Fig. 1, portions of the framework of the vehicle being omitted; Fig. 3 50 is a horizontal section on an enlarged scale, taken approximately on the line 3—3 of Fig. 1; Fig. 4 is a fragmental vertical section showing the latch mechanism which prevents the vehicle body from tilting; and

Fig. 5 is a plan showing one member of the 55 turntable.

In the accompanying drawings, the numeral 1 denotes the frame of a vehicle, including side bars 2 connected by cross bars 3 which may be angle members. The 60 numeral 4 marks, generally, a turntable, including a lower member 5 secured to the cross bars 3. The lower member 5 of the turntable 4 is supplied in its upper surface with a ball race 6 and has seats 7 about its 65 periphery. The turn table includes an upper member 8 having a ball race like the ball race 6 of the lower member 5. Balls 9 are interposed between the members 8 and 5 of the turn table 4 and support the upper member 8 of the turn table anti-frictionally. The members 5 and 8 of the turn table 4 are connected centrally by means of a pivot member 10 which permits the upper member 8 to rotate in a horizontal plane 75 with respect to the lower member 5, without, however, permitting the upper member to tilt vertically with respect to the lower member. The upper member 8 of the turn table 4 is supplied with oppositely disposed 80 upstanding bosses 11. The numeral 12 marks a carrier preferably in the form of a channel or beam having its flanges upwardly extended, although the carrier may be of any desired form. The carrier 12 is 85 secured to the bosses 11 of the upper member 8 of the turn table 4. The carrier 12 projects forwardly beyond the upper member 8 of the turn table, as clearly disclosed in Fig. 1. 90

The numeral 14 designates a vehicle body of any desired sort, united intermediate its ends, by means of a hinge 15, with the carrier 12 adjacent to the rear end of the carrier. 95

A cross beam 16 is secured to the under side of the body 14 adjacent the forward end thereof and, when the body is in a horizontal position, as shown in Fig. 1, the cross beam rests on the carrier 12. The forward end of the body 14 is supplied with bearings 17 in which is journaled a shaft 18 extended entirely across the forward end of the body. A lever 19 is secured to the shaft 18 at one side of the carrier 12 as shown in Figs. 1 100 and 2. The lever 19 carries a latch mechanism 21 adapted to coöperate with a segment or keeper 22 mounted on the end of

the body 14. Arms 23 are secured to the ends of the shaft 18 by means of set screws 24 or otherwise, the arms extending upwardly. The forward ends of connections 25 are pivoted to the upper ends of the arms 23, the connections being longitudinally adjustable, since turnbuckles 26 are interposed therein. An end gate 27 is hinged at the upper edge, as shown at 28, 10 to the body 14, the hinge including, if desired, a pivot rod 29, shown best in Fig. 2. The rear ends of the connections 25 are pivoted to the end gate 27 adjacent the lower edge thereof, and, if desired, the 15 pivotal connection between the rear ends of the members 25 and the end gate 27 may include a transverse rod 100 secured to the end gate.

A yoke 30 is disposed in front of the 20 body 14 and straddles the forward end of the carrier 12, the yoke including rearwardly extended downwardly inclined fingers 31, the yoke being fulcrumed as shown at 32 on a rod extended across the carrier 25 12 and mounted in the side flanges of the carrier. If desired, the rod 32 may pass through a portion of a segment 35 secured to the base of the carrier 12, the segment being adapted to coöperate with a latch mechanism 34 mounted on a handle 33 attached to the yoke 30, the handle and the yoke constituting a lever. Base plates 36 are secured to the cross beam 16 on the body 14, and from the base plates project knuckles 35 37 in which is mounted a shaft 38, shown clearly in Fig. 3. Depending arms 39 are secured to the ends of the shaft 38 and are pivoted at 40 to the forward end of the fingers 31 which form a part of the lever 40 30-33.

A latch 41 is pivoted at 42 to one of the side flanges of the carrier 12 and includes a nose 43 adapted to coöperate with the shaft 18 on the forward end of the body 14 45 in a manner to be described hereinafter. The latch 41 may include a depending grip 44 whereby the latch may be manipulated by hand. Preferably however, the latch is operated by means of a connection or rod 50 46 mounted to slide in a guide 47 secured to the base of the carrier 12 and terminating in a handle 48. The latch 41 is drawn forwardly to engage with the shaft 18, by means of a spring 45, one end of which is 55 attached to one of the side flanges of the carrier 12, the other end of the spring being attached to the latch, as clearly shown in Fig. 4.

A latch rod 49 slides vertically in one of 60 the bosses 11 of the upper member 8 of the turn table 4 and is adapted to coöperate with any of the notches or seats 7 which are formed in the edge of the other member 5 of the turn table as shown at 7 in Fig. 5.

65 The upper end of the latch rod 49 is

loosely connected with a bell crank lever 50 fulcrumed on a rod 51 extended transversely of the carrier 12 and mounted in the side flanges of the carrier, the bell crank lever being prevented from shifting its position 70 longitudinally of the rod, by means of collars 52 mounted on the rod, on each side of the bell crank lever. The numeral 53 denotes a connection, preferably in the form of a rod, the rear end of the connection being pivoted to the upstanding arm of the bell crank lever 50. The connection 53 slides longitudinally in a guide 54 mounted on the base of the carrier 12. An abutment 55 is secured to the connection 53, to 80 the rear of the guide 54. A compression spring 56 surrounds a portion of the connection 53, one end of the spring abutting against the member 55 and the other end of the spring abutting against the guide 54. 85 The forward end of the connection 53 is pivoted to a lever 57 fulcrumed at 58 on one of the side flanges of the carrier 12.

When the parts are arranged as shown in Fig. 1, body 14 is in a horizontal position, 90 the cross beam 16 resting on the carrier 12. The lever 19 is swung downwardly, thereby rotating the shaft 18, and swinging the arms 23 forwardly, the connections 25 moving forwardly and holding the end gate 27 in a closed position, the latch mechanism 21 being engaged with the segment 22 to hold the end gate 27 closed. The spring 56 forces the connection 53 rearwardly and tilts the bell crank lever 50 on its fulcrum 51, thereby causing the latch rod 49 to engage in one of the seats 7 in the lower member 5 of the turn table 4, thus holding the carrier 12 and the body 14 in vertical alinement with the frame 1. The spring 45 swings the latch 105 41 rearwardly, the nose 43 of the latch engaging with the shaft 18, thereby to prevent the body 14 from swinging downwardly at its rear end on the hinge 15.

The connection 53 may be drawn forwardly by means of the lever 57, thereby tilting the bell crank lever 50 and elevating the latch rod 49 out of one of the seats 7 in the lower member 5 of the turn table 4. Thereupon, the upper member 8 of the turn 115 table, the carrier 12 and the body 14 may be swung around in a horizontal plane, so that the body may discharge laterally in any desired direction, the latch rod 49 being engaged in the appropriate one of the seats 7 120 to hold the body 14 in any position to which it may have been rotated.

The lever 33 is disconnected from the segment 35 and the lever is tilted, whereupon the fingers 31 of the yoke 30 which forms 125 part of the lever will through the instrumentality of the arms 39, raise the forward end of the body 14, the body tilting on the hinges 15. The latch mechanism 21 on the lever 19 may be released from the segment 130

22 and the connections 25 may be operated by means of the shaft 18 and the arms 23, the shaft being rotated by the lever 19. In this way, the end gate 27 may be opened, 5 thereby permitting a dumping of the load.

The device forming the subject matter of this application is simple in construction and includes efficient means whereby the body 14 may be operated in the various 10 ways necessary, in a device of the kind hereinbefore described.

Having thus described the invention, what is claimed is:—

1. In a device of the class described, a vehicle frame; a turn table on the frame; a carrier secured to the turn table; a body pivoted to the turn table for vertical swinging movement and including an end gate; means for operating the end gate, comprising a 15 shaft journaled on the forward end of the body; and a latch mounted to swing on the carrier, the latch coöperating with the shaft to hold the body releasably against vertical swinging movement.

25 2. In a device of the class described, a vehicle frame; a turn table on the frame and comprising a fixed lower member and a rotatable upper member; a channel beam secured to the upper member of the turn table 30 and comprising upstanding flanges, the beam projecting beyond the periphery of the turn table a distance approximating the diameter of the turn table; a body supported on

the beam at a point above the turn table and at a point beyond the periphery of the 35 turn table; a latch forming a detachable connection between the members of the turn table; a shaft mounted at its ends in the flanges of the channel beam; a lever fulcrumed on the shaft, between the flanges, 40 and operatively connected with the latch; and means for operating the lever from a remote point.

3. In a device of the class described, a vehicle body; a turn table comprising a lower 45 member fixed to the body, and an upper member mounted to rotate with respect to the lower member; a latch mounted to slide vertically in the upper member, the lower member having spaced seats wherewith the 50 latch is adapted to engage; a beam mounted on the upper member of the turn table and projecting therebeyond; a bell crank lever fulcrumed on the beam and connected with the latch; means for operating the bell crank 55 lever from a remote point; and a body supported on the beam at a point above the turn table, and a point beyond the periphery of the turn table.

In testimony that I claim the foregoing 60 as my own, I have hereto affixed my signature in the presence of two witnesses.

JOHN P. BEATTY.
